UNITED STATES PATENT OFFICE.

CHARLES D. BLINN, OF PORT HURON, MICHIGAN.

IMPROVED MODE OF CLEANING LAMP-CHIMNEYS.

Specification forming part of Letters Patent No. 39,792, dated September 8, 1863.

To all whom it may concern:

Be it known that I, CHARLES D. BLINN, of Port Huron, in the county of St. Clair and State of Michigan, have invented a new and Improved Device for Cleaning Lamp-Chimneys; and I do hereby declare that the following is a full, clear, and exact description of the same, reference being had to the accompanying drawing, making a part of this specification, said drawing being a side view of my invention, partly in section.

This invention consists in the employment or use of two bars or rods connected by a fulcrum-pin, and having a suitable fibrous material attached to one end, the parts being so arranged as to form a very convenient and efficient device for the purpose of cleaning lamp-chimneys.

To enable those skilled in the art to fully understand and construct my invention, I will proceed to describe it.

A A represent two rods, which may be of wood and of slightly-curved form, as shown clearly in the drawing. These two rods cross each other, and are connected by a fulcrum-pin, *a*. The rods A A are curved in such a manner that they cross each other twice, so that by pressing the two rods together at one end the opposite ends will be spread apart. The fulcrum-pin *a* does not pass through the center of the rods, but at a considerable distance at one side thereof, and at the ends of the long arms of the rods there is attached cotton or woolen twist *b*, or other suitable fibrous material. This twist or other substance may be drawn through or into holes *c*,

made transversely in the ends of the rods, so as to form tufts at the outer sides of the rods, as plainly shown in the drawing. This fibrous material serves as a cleaner.

The device is used as follows: The lamp-chimney is grasped by the left hand of the operator, the latter with his right hand grasping the rods A A and closing the long arms of the rods, so that they may be inserted into the chimney, the chimney or rods being then turned and the short arms of the rods gently compressed, so that the long arms will have a tendency to expand or separate, and the twist or other substance *b* made to press against the inner surface of the chimney and effectually cleanse the same, the twist under the action of the rods being made to press sufficiently hard against the inner surface of the chimney and adjust itself to all parts of the same. This will be fully understood by referring to the drawing, in which the long ends of the arm are shown in the neck or narrow part of the chimney in red.

Having thus described my invention, what I claim as new, and desire to secure by Letters Patent, is—

A cleaner for lamp-chimneys, composed of two rods, A A, connected by a fulcrum-pin, *a*, and provided at one end with cotton or woolen twist or other fibrous material, substantially as set forth.

C. D. BLINN.
